DESIGN FOR A JEWELRY CASE OR THE LIKE

Leo Flier, Springfield, Mass.

Application January 14, 1942, Serial No. 165,195

Term of patent 14 years

To all whom it may concern:

Be it known that I, Leo Flier, a citizen of Russia and a resident of Springfield, in the county of Hampden and State of Massachusetts, have invented the new, original, and ornamental design for Jewelry Case or the like, of which the following is a specification, reference being had to the accompanying drawing, forming part thereof, in which—

Fig. 1 is a top plan view of a jewelry case in closed position showing my design;

Fig. 2 is a perspective view showing the bottom and one side of the case;

Fig. 3 is a view of the case in open position showing the inside thereof; and

Fig. 4 is a side elevational view showing the case supported by the standard which is provided on the base.

The dominant feature of my design resides in the flaring V-like contour and shape of the case substantially as shown.

I claim:

The ornamental design for a jewelry case or the like, substantially as shown and described.

LEO FLIER.
